ELECTRIC REGULATION

John L. Creveling, near Tucson, Ariz.

Application November 15, 1944, Serial No. 563,502

22 Claims. (Cl. 322—82)

1

My invention pertains to that class of electric regulation wherein the voltage upon or the current in an electric circuit is to be controlled automatically.

An object of my invention is to provide a sensitive regulator having relatively wide range which may be of small dimensions and cheaply built.

Another object is to provide an automatic regulator which shall come into action only when its services are required. Other objects will be pointed out in the specification or obvious thereto from those skilled in the art.

As my invention is particularly applicable to systems wherein the dynamo or generator subject to intermittent operation and wide changes in speed is employed to charge a storage battery and supply lamps or other translating devices, it will be described with particular reference to such a system.

Fig. I is a more or less diagrammatic representation of a system included in my invention, showing some parts in elevation, some in section, and some in diagram.

Fig. II includes a section of a commercial type of regulator comprehended by my invention, which is shown in a system having an auxiliary device which may be employed if desired. Fig. III is a partial section and partial elevation of a modified form of my invention adapted to control both the current and voltage of a generator.

Insofar as common subject matter appears, this is a continuation of my applications for patent for improvements in Electric regulation, No. 520,739, filed February 2, 1944, and No. 539,931, filed June 12, 1944, now Patent No. 2,441,059 of May 4, 1948.

In Fig. I, which is more or less of a laboratory type of apparatus, 1 indicates a dynamo or generator having the shunt field coil 2, one end of which is connected with one brush of the generator and the other with the upper end of the carbon pile 3 as by wire 4 while the lower end of the pile 3 is connected with the opposite side of the generator, as by wire 5. The pile 3 is compressed between the upper pressure plate 6 carried by lever 7 and the lower pressure plate 8 carried by the lever 9 due to the action of spring 10 which tends to draw the levers together about their pivots 11 and 12. The pile is insulated from the pressure plates as indicated and may be held in position with respect to the pressure plates by any of the usual means (not shown) such as external insulated rods or the discs may be perforated and threaded upon a rod of insulating material. The spring 10 acts upon the levers 7

2

and 9 through the instrumentality of the adjustable screw and nut arrangement indicated at 13 and the headed rod 14 which has its head bearing upon the arched bi-metallic strip 15, the function of which will be explained. The lower pressure plate 8 is connected with the curved member 16 bearing upon the steel spring 17 having its ends supported in any suitable manner as indicated at 18, tending to move the levers and pile 3 upwardly until arrested by the adjustable screw 19. The screw 19 is here shown as electrically connected with the wire 4 while the end of lever 7 is shown as insulated and connected as by wire 20 with the right-hand brush of the generator to indicate that this contact between 7 and the screw 19 may be used to short-circuit the pile at this time if desired. The spring 17 is clamped between the member 16 and member 21 as by screws indicated at 22 and member 21 is attached to the disc armature 23 of the ironclad electromagnet comprising the shell 24, core 25 and winding 26, which may be supported by any suitable means (not shown) in substantially the position indicated. The right-hand brush of the generator is connected by wire 26 with one side of the storage battery 27 and translating devices 28 having their opposite terminals connected with the wire 29 leading to one side of any suitable automatic switch, the mere presence of which is indicated at 30, as these switches or reverse current relays are well known in the art. The switch 30 has its opposite side connected through the removable link 31 with the left-hand brush of the generator 1. The opposite terminals or connectors of the link 31 are connected as by wires 36 and 37 with the ends of the solenoid 38 surrounding the core 39 of iron or other suitable magnetic material adapted when moved upwardly to engage the extension of lever 9 and tend to rotate the lever in a counter-clockwise direction. While the solenoid is short-circuited when the link 31 is in place as shown, if the link be removed the solenoid 38 will be placed in series with the generator and its load and the portion of the generator current which will traverse the solenoid may be adjusted as by the adjustable shunt indicated at 40. Attraction of armature 23 by magnet 24, 25, 26 tends to move the levers 7 and 9 and pile 3 downwardly against the effort of spring 17 without materially affecting the effect of spring 10 upon the pile until lever 7 strikes the adjustable screw 35 and then any further downward movement of the armature elongates the spring 10 to relieve the pressure upon the pile 3. Screw 35 is here shown as connected with the wire 34,

which may be connected with any suitable point upon resistor 33, so as to short-circuit a portion thereof for the purpose of adjustment, if this be desired.

In Fig. II the field coil 2 is connected with the pile 3 as in Fig. I by wires 4 and 14 but wire 4 is shown as having interpolated therein the winding 41 upon the core 42 of an auxiliary device which may be employed if desired. Core 42 rests upon the base 43 of insulating material and has, clamped between it and the base, a flexible strip serving as a hinge at the lower end of armature 44. Armature 44 carries the contact member 45 adapted to strike the contact member 46 carried by the member 47 when the armature 44 is attracted toward core 42. 48 is a leaf spring tending to hold armature 44 against the stop 49 of non-magnetic material while 50 is a bendable member for adjusting the effort of spring 48. Member 47 is connected with wire 14 as by wire 51 and core 42 is connected as by wire 52 with the stationary contact member 53 normally in contact with the armature 54 of the electromagnet 55, said contact being due to spring 56. Armature 54 is connected as by wire 57 with one end of the adjustable resistor 58 having its opposite end in communication with the wire 4. Thus, when contact is made at points 45—46 the resistor 58 is placed in shunt to the pile 3 to lighten the load upon the pile to the extent that may be desired. The winding of magnet 55 has one end connected with the wire 26 by wire 59, while the opposite end is connected by wire 60 with the wire 37 and thus with the opposite lead of the generator. The pile 3 is here shown as composed of perforated discs within the bore of the body portion 63 having heat dissipating fins 64 and preferably made of non-magnetic metal. The discs are insulated from the body portion by a thin tube of insulating material 65, and from the pressure plates 67 and 68, as indicated. The rod 66 passes through the perforations in the discs without contact and has its lower end attached to the member 67 while its upper portion passes through the pressure plate 68 and its stem 69 surrounded by the threaded sleeve 70 within the screw plug 71. The washer 72 bears upon the stem 69 and supports the spring 73 against which washer 74 may be drawn as by the nut 75. As rod 66 passes freely through the pressure plate 68 and its stem 69, and stem 69 passes freely through the bore of sleeve 70, the pile 3 is compressed between the lower pressure plate 67 and the upper pressure plate 68 by the spring 73 and also by spring 77 resting upon the ledges 78 and pressing upwardly against member 76 attached to member 67. Armature 23 is attached to the member 76 as by screws 80 passing through the member 79 and clamping the spring 77 between members 76 and 79. Therefore, if armature 23 be drawn downwardly as by magnet 24, 25, 26 it will not materially affect the pressure upon the pile due to spring 73 until washer 72 strikes the top of the adjustable sleeve 70, and then any further downward movement of armature 23 will relieve the pressure upon pile 3.

In Fig. III the parts above the magnet 24, 25, 26 are assumed to be the same as in Fig. II while the lower portion of said magnet carries the member 81, which in turn carries the magnet comprising shell 82, core 83 and winding 84 here shown as a coarse winding adapted to be placed in series with the generator as by wires 85 and 86. The shell 82 carries the member 87 which supports the spring 88 which may comprise a per-

forated leaf or a pair of imperforate leaves clamped between members 89 and 90 carried by the tube 91 which passes freely through the bore indicated in core 83 and which surrounds the rod 92 attached to the armature 23, which rod may move freely through the bore of magnet 25 and tube 91. Rod 92 is provided at its lower end with a nut 93 which may be adjusted to be engaged by the lower end of tube 91 when the armature 94 carried at the upper end of the tube is drawn downwardly by the magnet 82, 83, 84, so that the magnet may then affect the operation of the regulator by adding its pull to that of magnet 24, 25, 26 upon armature 23. Member 87 carries a flexible insulated spring strip 95 provided with the contact 96 adapted to engage the contact 97 when the parts are in the positions shown in the drawing while the contacts may be separated upon downward movement of rod 92. Member 81 may be provided with windows as shown at 98 while member 87 may have windows as indicated at 99 permitting observation and adjustment of the parts. Tube 91 carries a nut 100 whereby its upward movement may be adjusted and the contact members 96 and 97 may be connected by wires 102 and 101 in shunt to the pile 3 (not shown in this figure) so as to short-circuit the pile when the contact is made, as when the parts are in the positions shown in the drawing.

An operation of my invention as indicated in Fig. I is substantially as follows:

If the generator be at rest the switch 30 will be open and the translating devices 28 may be supplied by the battery 27 in the usual manner.

If the generator be started and gradually brought up to full speed and the left-hand brush be taken as positive, current will flow through the field coil 2, wire 4, pile 3, wire 5 and wire 26 back to the generator, but this will only be a very weak current so long as the end of lever 7 remains in contact with the screw 19, as the pile 3 is then short-circuited through the wire 20 to cause the generator field to build up as rapidly as possible upon starting. Current will also flow through wire 32 to the winding 26 of the magnet 24, 25, 26 and return through adjustable resistor 33 and wire 26 to the generator. This will cause the magnet to tend to draw armature 23 downwardly against the effort of spring 17 and by properly selecting the spring 17 and adjusting the resistor 33 the magnet may be caused to move its armature to relieve the pressure of 17 upon the pile and draw the parts connected with the armature downwardly so as to draw lever 9, pile 3, lever 7 and spring 10 downwardly and break the connection at screw 19 when the desired voltage is reached upon the generator. At the time the contact of lever 7 and screw 19 is broken the pile 3 is at the maximum compression spring 10 is capable of exerting and remains substantially so until lever 7 has its downward movement arrested by the screw 35 and then any further downward movement of armature 23 will lessen the pressure upon the pile 3 and increase the resistance thereof. And, as here shown, screw 35 may be connected as by wire 34 with any desired point upon the resistor 33 so as to short-circuit a portion thereof if desired for the purpose of adjustment of the current in winding 26 at this time. With this type of electromagnet indicated in a general manner in the drawing at 24, 25, 26 the pull per ampere turn increases very rapidly as the armature approaches the magnet and I so adjust the screw 35 that it will arrest the move-

ment of lever 7 at such a point that the voltage to be held constant throughout the tendency to rise will cause magnet 23, 24, 25 to so attract the armature 23 and relieve the pressure upon pile 3 as to prevent this voltage from being appreciably exceeded. This may be accomplished by allowing the armature to assume a position in the field of the magnet that causes substantially the same number of ampere turns to balance the effort of spring 10 and the elasticity of the pile as is required to move lever 7 into contact with screw 35, while further adjustment may be made by properly varying the effective value of resistor 33 upon contact with screw 35 if desired through connection of wire 34 with the proper point thereon.

With this arrangement the magnet will not appreciably affect the pressure upon pile 3, due to spring 10, during the building up of generator voltage to the maximum value to be held upon the generator, but when this value is reached may cause the same to be held constant throughout its tendency to increase within very narrow limits. And, if the generator be running under such condition that appreciable resistance has been inserted by reducing the pressure upon the pile 3, and then slow down, the reverse cycle will take place in an obvious manner.

It will here be noted that if contact of lever 7 with screw 19 be not employed to short-circuit the pile as when the connection of screw 19 with wire 4 is omitted, the initial movement of armature 23 will relieve the pressure of spring 17 to affect the field current before relieving the pressure due to spring 10 and that the joint action of spring 10 and spring 17 may cause the resistance of the pile to be so low that short-circuiting may not be desired in many cases.

When the generator voltage, during the above process reaches substantially that of the battery, the main switch 30, if properly chosen, will close and connect the generator with the battery and translating circuit to supply the same in a well-known manner under voltage regulation. If desired to prevent the generator current from exceeding a certain limit this may be accomplished by removing the link 31, whereupon the generator current or a portion thereof as determined by resistor 40 may be caused to pass through the solenoid indicated at 38 which is so arranged that when the current therein reaches a maximum desired value, it will raise the core 39 into contact with the extension of lever 9 and prevent this maximum value from being materially exceeded.

As the winding 26 becomes heated, due to the current therein, its resistance will of course rise and tend to alter the adjustment of the regulator. This may be overcome by the well-known method of a "swamping" resistance at 33 or by the device indicated at 15 or both. For, as the coil 26 becomes heated, the parts associated therewith will also have their temperature raised and 15 indicates an arched bi-metallic member which flattens upon temperature rise, so as to alter the effort of spring 10 in such manner as to tend to compensate for the resistance rise in coil 26.

In the structure of Fig. II the carbon pile is connected in series with the field coil 2 across the generator by wires 4 and 14 as in Fig. I, but the wire 14 has inserted therein the magnet coil 41, which may be employed for a purpose which will hereinafter be pointed out, and the coil 26 is across the generator circuit as by wires 60, 61 and 62. Therefore, when the generator voltage reaches the value which it is desired not to be exceeded, magnet 24, 25, 26 may, by proper ad-

justment, be caused to relieve the pressure of spring 77 upon the pile and draw the armature 23, members 79, 76, 67, carbon pile 3, rod 66, pressure plate 68 and its stem 69, washer 72, spring 73, washer 74 and nut 75 downwardly until washer 72 strikes the adjustable sleeve 70, without materially altering the pressure upon pile 3 due to spring 73 and then any tendency in generator voltage to rise will cause magnet 24, 25, 26 to draw the armature 23 downwardly against the effort of spring 73 so as to relieve the pressure upon pile 3, and, by thus raising its resistance prevent the generator from exceeding this desired voltage as explained with respect to Fig. I.

When the generator is operating at a speed just sufficient to produce the desired maximum voltage or when carrying a heavy load, it will require the greatest field current, and as this passes through coil 41, this coil may be caused to attract its armature 44 and close the contact at 45, 46, which will cause the resistor 58 to be placed in shunt to the pile 3 so as to relieve the same of a part of the field current until action of the pile has so weakened the field, as upon increase of generator speed or lessening of the load, that spring 43 is able to break the contact at 45, 46. And, since the current carried by the resistor 58 passes through the contact member 53 and armature 54, this circuit may be caused to be opened by voltage magnet 55 if for any reason the voltage of the generator tend to increase above a desired value and require the full range of the pile for its control.

In the structure of Fig. III the magnet 24, 25, 26 and the parts assumed to be above the same will operate in the same manner as in Fig. II if connected in the same way, though of course, the shunting device operated by magnet 41, 42 may be omitted in the structure of either figure unless desired to increase the carrying capacity of the regulator above that of the pile alone.

With this structure, if the wires 85 and 86 be connected as 36 and 37 are in Figs. I and II and the link 31 removed, the generator current will pass through winding 84 and cause the magnet 82, 83, 84 to tend to draw its armature 94, tube 91, members 89 and 90, and nut 103 downwardly against the action of spring 88. By properly adjusting the parts and the current in winding 84, as by means of a shunt as shown at 48 in Fig. I, the desired maximum generator current may readily be caused to bring the end of tube 91 into contact with nut 93 and by drawing the rod 92 downwardly prevent this current value from being materially exceeded.

It will be noted that the members 16 in Fig. I, 76 in Fig. II and 89 in Fig. III all have curved lower faces bearing upon their respective springs. This curvature is such that, as these members are drawn downwardly, they increase the bearing upon the springs in such manner as to give the springs the proper pull characteristic to compensate for the variation in pull of the magnets upon their armatures upon alteration of the air gap. Further, it is obvious that springs 17 of Fig. I and 77 of Fig. II may be so designed and arranged that, when the piles 3 are under maximum compression and in the positions shown in the figures the effect of said springs upon the piles may be either quite material or inconsequential as desired.

If wires 101 and 102 of Fig. III be connected across the pile 3 as by being connected with wires 4 and 14 shown in Fig. II, the contact 96, 97 may be caused to short-circuit the pile until armature

23 is drawn downwardly and rod 32, by flexing spring 95 opens the contact to produce the same result as breaking the contact between the end of lever 7 and screw 19 in Fig. I.

From the foregoing it will be seen that I have produced a regulator which will not affect the generator until its voltage reaches the desired maximum value and then will hold the same substantially constant throughout further increases in speed and it will be obvious that the current may be controlled in the same manner as the voltage by using a current winding in the structures where I have shown only voltage windings.

I do not here limit myself to any of the exact constructions shown nor to any of the particular modes of operation herein described, which have been set forth merely to illustrate a few embodiments of my invention, which is as set forth in the following claims.

I claim:

1. Regulating means including a regulating element, means tending to decrease the resistance of said element, automatic electromagnetic means having an air gap for moving said element and the resistance decreasing means a predetermined distance functionally to affect the automatic means by changing the length of the air gap without materially affecting the resistance of said element and means whereby further movement of a portion of the resistance decreasing means increases the resistance of said element.

2. Regulating means including a regulating element, means tending to decrease the resistance of said element, automatic electromagnetic means for moving said element and the resistance decreasing means a predetermined distance to adjust the electromagnetic operating characteristic of the moving means without materially affecting the resistance of said element, means whereby further movement of a portion of the resistance decreasing means increases the resistance of said element, said moving means so moving said portion.

3. Regulating means including a regulating element, means tending to decrease the resistance of said element, electromagnetic means for moving said element and the resistance decreasing means a predetermined distance to adjust the electromagnetic operating characteristic of the moving means without materially affecting the resistance of said element, means whereby further movement of a portion of the resistance decreasing means increases the resistance of said element, said moving means including electro-magnetic means for so moving said portion.

4. Regulating means including a regulating element, means tending to decrease the resistance of said element, electromagnetic means for moving said element and the resistance decreasing means a predetermined distance to adjust the electromagnetic operating characteristic of the moving means without materially affecting the resistance of said element, means whereby further movement of a portion of the resistance decreasing means increases the resistance of said element, said moving means including electromagnetic means for so moving said portion in response to fluctuations in an electrical quantity to be regulated.

5. Regulating means including a regulating element affected by variation in pressure thereupon, means for exerting pressure upon said element, electromagnetic means for moving said element without materially affecting the pressure exerted by the pressure exerting means thereupon the

magnetic effort of which is functionally affected by said movement and means causing further movement of said moving means to alter the pressure upon said element.

5 6. Regulating means including a regulating element the effect of which is varied by variation in pressure thereupon, means for exerting pressure upon said element, means for moving said element without materially affecting pressure upon said element, said movement functionally affecting the effort of the moving means and means causing said moving means to vary the pressure upon said element.

15 7. Regulating means including a regulating element the effect of which is varied by variation in pressure thereupon, means for exerting pressure upon said element, electro-magnetic means for moving said element without materially affecting pressure upon said element, said movement functionally affecting the effort of the moving means and means causing said moving means to vary the pressure upon said element.

20 8. Regulating means including a regulating element the effect of which is varied by variation in pressure thereupon, means for exerting pressure upon said element, electro-responsive means for moving said element without materially affecting pressure upon said element, said movement functionally affecting the effort of the moving means and means causing said moving means to vary the pressure upon said element.

25 9. Regulating means including a regulating element the effect of which is varied by variation in pressure thereupon, means for exerting pressure upon said element, voltage-responsive means for moving said element without materially affecting pressure upon said element, said movement functionally affecting the effort of the moving means and means causing said moving means to vary the pressure upon said element.

30 10. Regulating means including a regulating element the effect of which is varied by variation in pressure thereupon, means for exerting pressure upon said element, current-responsive means for moving said element without materially affecting pressure upon said element, said movement functionally affecting the effort of the moving means and means causing said moving means to vary the pressure upon said element.

35 11. Regulating means including a regulating element the effect of which is varied by variation in pressure thereupon, means for exerting pressure upon said element, electromagnetic voltage and current responsive means for moving said element functionally to vary the effort per ampere turn of the electromagnetic means without materially affecting pressure upon said element and means causing said moving means to vary the pressure upon said element.

40 12. Means for regulating a generator having a field, comprising means for controlling a generator field including a regulating element, means affecting the regulating effect of said element, means for moving said element and said affecting means without materially affecting the regulating effect of said element including an electromagnet and an armature and means whereby said moving means may affect the effect of said magnet per ampere turn upon said armature.

45 13. Means for regulating a generator having a field, comprising means for controlling a generator field including a regulating element, means affecting the regulating effect of said element, means responsive to a function of generator output for moving said element and said affecting

means functionally to affect the moving means by varying the responsiveness thereof without affecting the regulating effect of said element and means whereby said moving means may affect the effect of said element to regulate a generator by controlling said field.

14. Means for regulating a generator having a field, comprising means for controlling a generator field including a regulating element, means affecting the regulating effect of said element, automatic means for moving said element and said affecting means to adjust the operating characteristic of the moving means without materially affecting the regulating effect of said element and means whereby said moving means may be caused to affect the effect of said element to regulate a generator by controlling said field in response to fluctuations tending to take place in a function of the output of the generator.

15. A generator regulator including a compressible rheostat, compressing means therefor, an electro-magnet adapted to be energized by a function of a generator output, an armature for said magnet located in a relatively weak portion of the field of said magnet till said function reaches a predetermined value and then moving toward said magnet into a relatively strong portion of said field and moving the compressing means without materially affecting the effect of the compressing means upon the rheostat and means whereby said armature while in said strong portion of said field may affect the compression of said rheostat.

16. Regulation means suitable for use in a system wherein a generator driven at variable speed is used to charge a storage battery, including a regulating element for affecting the generator voltage upon changes in pressure applied to said element, means for applying pressure upon said element, means for controlling the pressure-applying means comprising an electro-magnet having a field which varies rapidly with respect to distance therefrom, an armature in said field, means for holding said armature in a weak portion of said field until a predetermined voltage is reached upon said generator and then permitting the armature to move into a strong portion of said field and while so doing move the said element and pressure-applying means without materially affecting the pressure applied by said means to said element, and means whereby movement of said armature while in said strong portion of said field affects the pressure upon said element to regulate the generator.

17. Regulating means including a regulating element, means for short-circuiting said element, and electro-magnetic means for moving said element to affect the magnetic circuit of the electro-magnetic means functionally and breaking said short-circuit without materially affecting the resistance of said element.

18. In a system employing a variable speed generator and a storage battery charged thereby, automatic means for regulating the genera-

tor against speed and load changes including a compressible rheostat controlling the generator output, means for compressing said rheostat, means responsive to a function of the generator output including an electro-magnet and an armature for moving the rheostat and compressing means without materially affecting the pressure exerted by the compressing means to vary the effect of said magnet per ampere turn upon said armature and means whereby said responsive means may be caused to affect the pressure upon said rheostat.

19. A regulator suitable for use in combination with a variable speed generator, and a storage battery charged thereby, including a carbon pile for regulating the generator and means responsive to a function of the generator output for operating said pile to regulate the generator by controlling the field current thereof, means responsive to changes in field current for varying the amount of said field current carried by said pile and means actuated by change in value of a function of generator output for affecting the operation of the said varying means.

20. Regulating means including a regulating element the effect of which is varied by variations in pressure thereupon, means applying pressure upon said element, means for adding pressure upon said element and electro-responsive means for moving the element and relieving the pressure due to said pressure adding means and then relieving the pressure due to the pressure applying means.

21. An electric regulator including a regulating element in an electric circuit, electromagnetic responsive means operating said element to control the current in said circuit, means controlled by the current in said circuit for diverting current around said element and automatic voltage responsive means for controlling the operation of said diverting means.

22. An electric regulator including a regulating element in an electric circuit, electromagnetic responsive means operating said element to control the current in said circuit, means controlled by the current in said circuit for diverting current around said element and automatic responsive means for affecting the operation of said last-mentioned means.
